APRON MOUNTING FOR AN EARTHMOVER
Harvey W. Rockwell, Cedar Rapids, and Dale W. Hawk,
Marion, Iowa, assignors to Allis-Chalmers Manufacturing Company, Milwaukee, Wis.

Filed June 11, 1964, Ser. No. 374,528
18 Claims. (Cl. 37—129)

This invention relates to an earthmover and particularly to the mounting arrangement of the apron on the scraper bowl side walls.

It is an important object of this invention to provide an earthmover which has maximum cutting edge width and maximum capacity for a given overall earthmover width.

It is a further object of this invention to provide an apron mounting wherein the apron arms are in alignment with apron actuating jacks mounted on the scraper bowl side walls.

It is a further object of this invention to provide an apron mounting on the scraper bowl side wall structures wherein the arms extend through horizontally aligned openings in the side wall structures.

It is a further object of this invention to provide an earthmover as set forth in the previous object and having recesses in the side wall structures to accommodate the apron operating jacks without increasing the overall width of the earthmover.

It is a further object of this invention to provide a mounting arrangement for the apron of an earthmover wherein the apron arms extend rearwardly along the inner side of the scraper bowl side walls and through openings in the side walls aligned with the arms and wherein pivot means are provided for the apron arms at the openings and for connection to the legs of a draft frame.

It is a further object of this invention to provide an earthmover having maximum cutting edge and apron width in relation to the overall width of the earthmover, an apron mounting wherein its arms extend through the side walls of the scraper bowl and connect to hydraulic jacks aligned with the apron arms and means pivotally connecting the apron and draft frame to the side walls on a common pivot axis.

It is a further object of this invention to provide an apron mounting for an earthmover wherein the apron arms extend through openings in the scraper bowl side walls and wiping means are provided to eliminate nut-cracker action on particles such as stones that might otherwise wedge between the apron arms and side walls.

These and other objects and advantages of this invention will be apparent to those familiar with the art when the following description is read in conjunction with the drawings in which:

FIG. 1 is a side view of an earthmover in which this invention is incorporated;

FIG. 2 is a top view of the earthmover shown in FIG. 1; and

FIGS. 3, 4, 5 and 6 are section views taken on the lines III—III, IV—IV, V—V and VI—VI in FIG. 1.

Referring to FIGS. 1 and 2 the earthmover in which this invention is incorporated includes a wheeled scraper bowl 11 having a pair of side wall structures 12, 13 rigidly interconnected by a bottom wall 14, a transverse beam 16 between the front ends of the wall structures 12, 13 and rear bracing 17. A draft frame 21 is connected at its front end to wheeled support means, not shown, includes a yoke-like part made up of a transverse box section member 22 and legs 23, 24 extending rearwardly therefrom closely adjacent to the outer sides of vertical outer walls 26, 27, respectively, of the side wall structures 12, 13. The legs 23, 24 are pivotally connected at

2

their rear ends to the side wall structures 12, 13, respectively, on transverse pivot axis 28.

A transversely extending blade 31 is rigidly secured to as by bolts, not shown, to the bottom wall 14 and hence to the side wall structures 12, 13. The blade 31 extends from outer wall 26 to outer wall 27. Longitudinally extending frame members in the form of channels 32, 33 are secured as by welding to the laterally outer side of outer walls 26, 27, respectively, and as seen in the drawings the outer side walls 26, 27 and channels 32, 33 extend the full length of wall structures 12, 13. The channel members are spaced vertically below the legs 23, 24 so as not to increase the overall width of the earthmover. The channels 32, 33 are spaced intermediate the pivot axis and the blade 31 so as to avoid interference with the legs 23, 24 during raising and lowering of the bowl by actuation of hydraulic jack 34 interconnected between the frame 21 and the front of the bowl 11.

Referring also to FIGS. 3, 4, 5 and 6 an apron 36 is approximately as wide as the lateral spacing between outer walls 26, 27 and has arms 37, 38 in the form of flat plates extending from the laterally opposite ends of the apron rearwardly in closing adjacent relation to the inner side of the outer walls 26, 27. The arms 37, 38 extend between outer walls 26, 27 and inner walls 39, 41 and are pivotally connected to the inner and outer walls by pivot means 83, 84, such as those shown in copending patent application Ser. No. 366,991 of Dale W. Hawk filed May 13, 1964, now Patent No. 3,295,234. Such pivot means may include a pivot pin member such as pin 43 to which leg 23 is pivotally connected.

The inner wall 39 is rigidly interconnected to the outer wall 26, by transverse plates 58, 81, 82 welded thereto, to form a pocket or recess 45 in the upper rear of side wall structure 12. A similar recessed portion 75 is formed in side wall structure 13 by inner wall 41 and appropriate transverse brace plates, not shown. The rear end portions 46, 86 of the apron arms 37, 38 are pivotally connected to the rod portion of hydraulic jacks 42, 72. As illustrated in FIG. 1 portion 46 is pivotally connected to the rod of actuator 42 by a transverse pin 47 and the cylinder of the actuator 42 is pivotally connected to the side wall structure 12 by pin 48. As illustrated in FIG. 2 the hydraulic jacks 42, 72 are in longitudinal alignment with apron arms 37, 38, respectively, thereby providing a straight line action of force through the jacks and arms. Placing the rams 42, 75 in the recesses 45, 75 avoids increasing the overall width of the earthmover yet permits a full width cutting edge and full width apron. It should be understood that the ejector 51 is shaped at its laterally opposite side edges to conform with the vertical contour of the recessed portions of the side wall structures. The inner walls 39, 41 terminate at their forward ends adjacent the openings at the forward extremities of the recesses 45, 75.

The apron arm 37 has arcuate surfaces 52, 53 which are coaxial to the axis 28 and are at diametrically opposite sides thereof, that is they lie on opposite sides of a plane through axis 28. The radially outer facing arcuate surfaces 52, 53, cooperate with wiping edges 54, 56 formed on transverse plates 57, 58 rigidly interconnected with the walls 26, 39. The edges 54, 56 are closely adjacent the arcuate surfaces 52, 53, respectively, throughout the movement of the apron between the closed position illustrated in FIG. 1 to an open position wherein the hydraulic jack 42 is substantially fully contracted. The inner surface 59 of outer wall 26 and the laterally inner edge 60 of the plate 57 are closely adjacent the vertical surfaces 61, 62 of the apron arm 37. Thus as the apron is pivoted between its open and closed positions the edges 54, 56 and side surfaces 59, 60 perform a wip-

ing action on the apron arm 37 to prevent excavated material from readily flowing into the recess 45 and preventing particles from wedging between the apron arm and the side wall structure. Thus nutcracker action on wedging rock or stone between the apron and side wall structure during operation of the apron is avoided. The surfaces 54, 56, 59 and 60 define a narrow vertically extending slot or opening in close fitting relation with the apron arm 37 and oriented longitudinally to receive the latter.

Although only the side wall structure 12 and the installation of apron arm 37 is fully described it should be understood that a similar construction is provided in side wall structure 13 for installation of apron arm 38 thereon. The inner walls 39, 41 terminate at their forward ends adjacent the openings at the forward extremities of the recesses 45, 75.

From the foregoing description it is apparent that our invention permits a maximum width cutting edge with a maximum bowl capacity for a specified width. The recesses 45, 75, permit the actuators 42, 72 to be disposed within such specified width and permit mounting the actuators in line relation to the apron arms 37, 38, thus eliminating the problems inherent in the dog leg or bell-crank type mounting of the apron arms heretofore used.

The embodiments of the invention for which an exclusive property or privilege is claimed are defined as follows:

1. An earthmover comprising:
a wheeled scraper bowl having a pair of side wall structures each including

a vertical outer wall extending forwardly to the approximate forward extremity of its related side wall structure and

an inner wall connected to said outer wall to form an outwardly facing recess therein and a longitudinally oriented opening at the forward end of said recess, said inner wall having its forward terminus approximately at the forward end of said recess,

an apron at the front of said bowl having a pair of laterally spaced arms extending rearwardly adjacent the inner side of said vertical outer walls, respectively, and through said openings, respectively,

a pair of pivot means at said openings pivotally connecting said arms to said side wall structures, respectively, for swinging movement about a transverse pivot axis between open and closed positions, each of said pivot means including a pivot member supported by said inner and outer walls of the associated side wall structure, and

a pair of hydraulic actuators disposed within said recesses, respectively, and having corresponding ends pivotally connected, respectively, to said side wall structures and said apron arms at points on the latter spaced from said transverse pivot axis.

2. The structure set forth in claim 1 wherein said hydraulic actuators are extensible and contractible hydraulic jacks and said apron arms are in longitudinal alignment with said jacks, respectively.

3. The structure set forth in claim 1 and further comprising a draft frame having a pair of legs extending rearwardly on the laterally outer side of said side wall structures, respectively, and pivotally connected thereto by said pivot means on said transverse pivot axis.

4. The structure set forth in claim 1 and further comprising upper and lower wiping edges at said openings between said inner and outer walls facing radially toward said transverse pivot axis and arcuate wiping faces on said apron arms in coaxial relation with said transverse pivot axis and in closely adjacent relation to said wiping edges, respectively, throughout the pivotal movement of said apron between said open and closed positions.

5. The structure set forth in claim 4 wherein said hydraulic actuators are extensible and contractible hy-

draulic jacks and said apron arms are in longitudinal alignment with said jacks, respectively.

6. The structure set forth in claim 5 and further comprising a draft frame having a pair of legs extending rearwardly on the laterally outer sides, respectively, of said side wall structures and pivotally connected thereto by said pivot means on said transverse pivot axis.

7. An earthmover comprising:
a scraper bowl having a pair of laterally spaced side wall structures each including
a vertical outer wall extending forwardly to the approximate forward extremity of its related side wall structure,
an inner wall spaced inwardly from and rigidly secured to said outer wall to define a recess, said inner wall terminating approximately at the forward end of said recess, and
wall means at the forward end of said recess defining a narrow vertically extending slot between said inner and outer walls,

an apron having arms extending rearwardly along the inner side of said outer walls, respectively, and having portions through said slots, respectively, pivot means pivotally connecting said arms to said inner and outer walls, respectively, adjacent said forward end of said recesses for swinging movement about a transverse pivot axis between open and closed positions,

power means for operating said apron disposed within said recesses, respectively, and connected to the associated apron arm portions.

8. The structure set forth in claim 7 and further comprising a blade secured to the front bottom of said bowl and extending between said outer walls and wherein said power means are positioned inwardly of said outer walls.

9. The structure set forth in claim 8 wherein said power means are extensible and contractible hydraulic jacks pivotally connected at their forward ends to said apron arm portions, respectively, and at their rear ends to said side wall structures, respectively, and wherein said apron arms are in longitudinal alignment with said jacks, respectively.

10. The structure set forth in claim 9 including radially outward facing arcuate surfaces formed on said apron arms, respectively, on opposite sides of a plane through said transverse pivot axis and upper and lower wiping edges at the top and bottom of said slots in closely adjacent relation to said arcuate surfaces throughout the movement of said apron between its open and closed positions.

11. The structure set forth in claim 7 including radially outward facing arcuate surfaces formed on said apron arms, respectively, on opposite sides of a plane through said transverse pivot axis and upper and lower wiping edges at the top and bottom of said slots in closely adjacent relation to said arcuate surfaces throughout the movement of said apron between its open and closed positions.

12. The structure set forth in claim 11 and further comprising vertical side faces on laterally opposite sides of said apron arms and laterally facing vertical surfaces on said side structures defining the laterally opposite sides of said slots and disposed in closely adjacent relation to said faces, respectively.

13. The structure set forth in claim 7 wherein said side wall structures each include a longitudinally extending frame member rigidly secured to the laterally outer side of its outer wall below its recess, said frame members being substantially coextensive in length with said outer walls and disposed intermediate the bottom of the latter and said pivot means.

14. The structure set forth in claim 7 and further comprising a cutting blade extending between and rigidly secured to said outer walls at the forward bottom portion of said bowl and wherein the lateral width of said apron is substantially the lateral distance between said outer walls.

15. The structure set forth in claim 14 wherein said recesses are disposed substantially in the upper rear quarter of said side wall structures, respectively.

16. The structure set forth in claim 15 wherein said actuators are extensible and contractible hydraulic jacks longitudinally aligned with said apron arms, respectively.

17. The structure set forth in claim 16 wherein elongated frame members are rigidly secured to and extend substantially the length of the laterally outer sides of said outer walls, respectively, said frame members being vertically spaced intermediate said pivot means and above said blade.

18. The structure set forth in claim 17 and further comprising a draft frame with longitudinally extending

legs vertically above said frame members and connected by said pivot means to said wall structures, respectively.
